UNITED STATES PATENT OFFICE.

HENRY KNOWLTON, OF WEST BAY CITY, MICHIGAN.

SALT-EVAPORATOR.

SPECIFICATION forming part of Letters Patent No. 269,945, dated January 2, 1883.

Application filed August 31, 1882. (No model.)

To all whom it may concern:

Be it known that I, HENRY KNOWLTON, of West Bay City, in the county of Bay and State of Michigan, have invented new and useful Improvements in Salt-Evaporators; and I hereby declare that the following is a full, clear, and exact description thereof, reference being had to the accompanying drawing, which forms a part of this specification.

10 My invention relates to improvements in apparatus for evaporating in grainers, and the novelty consists in the construction and arrangement of parts, as will be more fully hereinafter set forth, and specifically pointed out in the claims.

15 In the accompanying figure of drawing which forms a part of this specification, a view in perspective of my improvement is shown; and in this drawing A represents a 20 steam-boiler set in the usual way over a furnace, which latter, however, is not shown. The drawing represents a return-flue boiler provided with a smoke-stack, B, at the front end, in the usual way. C is the steam-dome, 25 from the top of which the branch pipe D carries the steam to the main pipe E, which communicates with the distributing-pipes F in the grainer G, such distributing-pipes and grainer being also of the usual construction. 30 The main pipe extends to and forms a connection with the smoke-stack, as shown. Another steam-pipe, H, also takes steam from near the top of the dome and carries it through the smoke-stack and discharges into the main pipe, thereby causing a vacuum at the point 35 of discharge, by means of which a portion of the products of combustion is drawn into the main steam-pipe and brought within the current of the steam therein. A plug like 40 that usually employed in injectors or ejectors may be employed, so that the discharge end of the steam-pipe H will have a more perfect effect. If preferred, a fan may be located in the smoke-stack and driven from any conven-

ient source of power, by means of which the 45 products of combustion will be driven into the main steam-pipe without departing from the spirit of my invention, or other devices that will accomplish the same result may be so employed. Near the exit-orifice of the smoke- 50 stack I place a damper, I, which, being above the point of intersection therewith of the pipes H E, allows the operator to compel all the products of combustion to pass through the main pipe E into the grainer, or any portion of such 55 products may be allowed to escape. I deem this construction important, as it frequently occurs in this art that it is desirable to reduce the temperature in the grainer suddenly, as well as to modify the draft in the furnace. I 60 can build a fire in my furnace also, when the steam is not working, by opening the damper I.

By commingling the heated gases of the furnace, as I have described, with the steam from the furnace or boiler, I am enabled, with a cer- 65 tain amount of fuel, to evaporate a much larger quantity of brine than can be done in the ordinary methods employed.

What I claim as my invention is—

1. The combination, with a steam-boiler and 70 salt-grainer, of the main steam-pipe communicating with the dome of the generator and the furnace of the boiler through the smoke-stack, which has an open pipe controlled by a damper, and an additional steam-pipe adapt- 75 ed to take steam from the generator, carrying the same through the smoke-stack and into the main steam-pipe, substantially as and for the purposes specified.

2. In combination with the boiler A, dome 80 C, main pipe E, the steam-pipes D H, and grainer, the smoke-stack B, having open tops controlled by damper I, as and for the purpose set forth.

HENRY KNOWLTON.
